ABSTRACT OF THE DISCLOSURE

Piezoelectric ceramic of the general formula

where the subscripts denote mole fractions and have the following values: $x=0\text{--}9$, $y=1\text{--}6$, $z=0\text{--}65$, and $x+y+z=1.00$, are improved by two coexistent additives; the first being .01 to .50 weight percent manganese monoxide (MnO) and the second selected from the group of .01 to .30 weight percent iridium dioxide (IrO_2) and .01 to .50 weight percent chromium sesquioxide (Cr_2O_3).

This invention relates generally to piezoelectric ceramic materials, and in particular to novel lead titanate zirconate base ceramics characterized by the incorporation of manganese monoxide (MnO) and one of iridium dioxide (IrO_2) and chromium sesquioxide (Cr_2O_3) as two co-existent additive agents.

It is the object of this invention to improve both the electromechanical coupling and the mechanical quality factors of piezoelectric ceramics.

It is well known that a solid solution of lead titanate zirconate [$\text{Pb}(\text{ZrTi})\text{O}_3$], produced by mixing together lead zirconate (PbZrO_3) and lead titanate (PbTiO_3) and sintering the mixture, exhibits enhanced piezoelectric properties, excellent temperature and time stability, and that the most salient piezoelectric properties are exhibited in the vicinity of $x=0.52\text{--}0.54$ for a generalized formula

It is also known that the basic criteria for assessing the merits of piezoelectric ceramic materials are the electromechanical coupling factor k_r and the mechanical quality factor Q_m . The former indicates the conversion efficiency in converting mechanical oscillation to electrical oscillation and vice versa while the latter indicates the order of the energy consumed within the ceramic material in the oscillation conversion; the larger the value of the mechanical quality factor, the less the amount of energy consumed.

Ceramic filters using piezoelectric ceramics as elements and mechanical filters using the same as transducers have been the subject of considerable recent research. The characteristics of piezoelectric ceramics called for in these applications may be summed up as follows:

The electromechanical coupling factor of any ceramic filter element may maintain any designated value ranging from an extremely small value to an extremely large value and at the same time, the mechanical quality factor of the element must be as large as possible. When utilized as a transducer element, it is desirable that both the electromechanical coupling factor and the mechanical quality factor be as large as possible. In other words, the characteristics required for a transducer element conform to the characteristics of materials for ceramic filter elements having particularly large electromechanical coupling factors.

Although the principal constituent components con-

templated by this invention are lead titanate zirconate the effect of coexistence of manganese monoxide and iridium dioxide (chromium sesquioxide) as two additives would remain the same even if 25 atom percent or less lead in the lead titanate zirconate is replaced with any one or a combination of any two or all of calcium, strontium, and barium; and/or 65 atom percent or less of the sum of titanium and zirconium is replaced with tin. These are substitutions well known to the art. Accordingly when hereinafter the term "principal constituent components" is used or lead titanate zirconate is being described as a component, it will be appreciated that the description applies equally to one in which either or both of the foregoing substitutions has been made. For further details of such substitutions, reference may be made to a treatise by B. Jaffe, R. S. Roth, and S. Marzullo in the Journal of Research of the National Bureau of Standards 55 (1955), page 239, and U.S. Patent No. 3,068,177.

It may be said therefore that this invention pertains to novel piezoelectric ceramic materials having essentially the constituency indicated by the generalized formula

wherein the subscripts denote mole fractions and have the following value:

$$\begin{aligned}x &= 0.00\text{--}0.90 \\y &= 0.10\text{--}0.60 \\z &= 0.00\text{--}0.65 \\x+y+z &= 1.00\end{aligned}$$

and, if required or desired, 25 atom percent or less lead is replaced with at least one of calcium, strontium, and barium; characterized by two co-existent additives as will be described.

It will be further apparent to those skilled in the art that the improvements in the characteristics (k_r and Q_m) caused by the incorporation of manganese monoxide and iridium dioxide (chromium sesquioxide) are due to manganese and iridium (chromium) ions present in lead titanate zirconate base ceramics. (Since iridium and chromium compounds are alternative second additive agent for convenience, the latter will be parenthetically recited to demonstrate that the use of either with manganese compounds is intended.) Accordingly, manganese compounds other than MnO (e.g., MnCO_3 or MnO_2) may be employed; the only requisite being that such a compound needs to contain the equivalent weight of manganese ions. Likewise, in incorporating an iridium compound other than IrO_2 (such as IrCl_3 or Ir_2O_3) as a chromium compound other than Cr_2O_3 (e.g., $\text{Cr}_2(\text{SO}_4)_3$ or CrO_3) such compounds need to contain the equivalent weight of ions.

The above mentioned and other features and objects of this invention and the manner of attaining them will become more apparent and the invention itself will be understood by reference to the following descriptive of embodiments of the invention taken in conjunction with the accompanying drawings wherein:

FIG. 1 graphically illustrates the electromechanical coupling and mechanical quality factors characteristic of the piezoelectric ceramics of the invention with or additive constant.

FIG. 2 graphically illustrates the electromechanical coupling and mechanical quality factors characteristic of the piezoelectric ceramics of the invention with the other additive constant.

FIG. 3 graphically illustrates the electromechanical coupling and mechanical quality factors characteristic of a piezoelectric ceramic with one variable additive alone.

FIG. 4 graphically illustrates the electromechanical coupling and mechanical quality factors characteristic

of a piezoelectric ceramic with the other variable additive alone.

The curves in FIG. 1 show the electromechanical coupling factor (abbreviated k_r) in radial mode and the mechanical quality factor (abbreviated Q_m) of piezoelectric ceramics having the principal constituent components expressed as $Pb(Zr_{0.52}Ti_{0.48})O_3$ and incorporating as the two additive agents 0.10 weight percent MnO , and: curve A—less than 0.30 weight percent IrO_2 in varying amounts as the variable; and curve B—less than 0.50 weight percent Cr_2O_3 as the variable.

It was experimentally verified that the values of k_r and Q_m for plain or unmodified lead titanate zirconate subjected to poling at room temperature were 41% and 270, respectively and that the corresponding values for the same ceramic subjected to poling at 100° C. were 42% and 250. FIG. 1 manifests that the incorporation of only 0.1 weight percent MnO contributes markedly to improvements in the piezoelectric characteristics and that incorporation of both MnO and IrO_2 or Cr_2O_3 contributes to much greater improvements.

Incorporation of IrO_2 in excess of 0.30 weight percent impairs formation of a solid solution of lead titanate zirconate and IrO_2 , resulting in lowering of the electrical resistivity and impracticability of poling. Therefore, the effective range for incorporation of IrO_2 is restricted to 0.30 or less weight percent (0.00 wt. percent is excluded). For similar reasons and reasons apparent from FIG. 1, the effective range of Cr_2O_3 is limited to 0.50 weight percent (0.00 wt. percent excluded).

FIG. 2 demonstrates the fact that the values of k_r and Q_m of a lead titanate zirconate ceramic containing only 0.10 weight percent IrO_2 (0.15 weight percent Cr_2O_3) have been remarkably improved over the corresponding values of k_r and Q_m of a plain lead titanate zirconate ceramic expressed as $Pb(Zr_{0.52}Ti_{0.48})O_3$. It also demonstrates that more excellent piezoelectric properties can be secured under coexistence of IrO_2 (Cr_2O_3) and MnO .

Further, improvements in the characteristics due to coexistence of the two additive agents cannot be expected where MnO exists in more than 0.50 weight percent. This is to say, the existence of the second additive IrO_2 (Cr_2O_3) in the presence of more than 0.50 weight percent MnO as the first additive does not materially improve the characteristics because the characteristics have been fully affected by the first additive and stabilized. In other words, the coexistence of MnO and IrO_2 (Cr_2O_3) becomes of no further significance. For this reason the range of effective incorporation of MnO has been restricted to 0.50 or less weight percent (0.00 weight percent is excluded).

The curves in FIG. 3 show dependence of k_r and Q_m of piezoelectric ceramics consisting of a lead titanate zirconate expressed as $Pb(Zr_{0.52}Ti_{0.48})O_3$ and less than 0.30 weight percent IrO_2 (0.50 weight percent Cr_2O_3) in varying amounts on the amount of IrO_2 (Cr_2O_3) taken as the variable.

The curves in FIG. 4 show dependence of k_r and Q_m of piezoelectric ceramics consisting of a lead titanate zirconate expressed as $Pb(Zr_{0.52}Ti_{0.48})O_3$ and less than 0.50 weight percent MnO in varying amounts on the amount of MnO taken as the variable.

The more detailed description which follows further clarifies the invention and the relationship between the embodiments.

Lead oxide (PbO), zirconium oxide (ZrO_2) and titanium oxide (TiO_2) were mixed in the ratio of 50:26:24 mole percent so that the principal constituent components may be expressed as $Pb(Zr_{0.52}Ti_{0.48})O_3$ and to this, required amounts of manganese monoxide (MnO) and iridium dioxide (IrO_2) were added. The mixture was thoroughly mixed in a ball mill, preheated at 900° C. for one hour, pulverized, and pressed to form disc-shaped samples. The samples were then sintered at 1300° C. for

one hour and a pair of silver electrodes were installed on the opposite surfaces of each disc. Then the samples were subjected to poling either at room temperature or at 100° C. by applying a voltage of 50 kv./cm. The samples were then left standing in the air for twenty-four hours and the values of k_r and Q_m of these ultimate products measured.

Normally, poling is performed at room temperature or at temperatures in excess of room temperature. In conducting these experiments, therefore, 100° C. was selected as a typical temperature above room temperature. Where the result was the same regardless of poling temperature, only one poling temperature will be described.

It is to be noted that (as will be seen from the tables) alternative ion sources were selected to illustrate the equivalency of additives (e.g., in some cases $MnCO_3$ was used instead of MnO).

Table I shows the values of k_r and Q_m for ceramics consisting of plain lead titanate zirconate, lead titanate zirconate and 0.10 weight percent MnO , and lead titanate zirconate, 0.10 weight percent MnO , and less than 0.30 weight percent IrO_2 in varying amounts, respectively.

¹ Denotes incorporation of MnO_2 in amounts equivalent to MnO .

² Denotes incorporation in the form of MnO instead of MnO_2 .

A comparison between samples No. 1 and No. 2 shows that incorporation of merely 0.10 weight percent MnO contributes appreciably to improvements in the value of k_r . Further, a comparison between samples No. 3 through No. 9 and sample No. 1 or No. 2 demonstrates that both k_r and Q_m are improved markedly in the presence of

both MnO and IrO_2 as coexistent additives. These embodiments also indicate that these materials, notably No. 3 through No. 9, are eminently suitable for ceramic filter materials for which large values of k_r are necessary or for transducer materials. It can further be noted that in the range where the incorporation of IrO_2 is small (such as samples No. 3 through No. 5) the value of k_r is markedly improved by poling at 100°C .

Table II illustrates similar results are attainable with Cr_2O_3 rather than IrO_2 as the second additive. From this table it may be seen that samples No. 3' through No. 7' subjected to poling at 100°C . would be excellent for ceramic filter elements for which particularly large values of k_r are called for or for transducer elements in mechanical filters and that samples No. 3' through No. 9' subjected to poling at room temperature could be adapted for ceramic filter elements for which extremely large values of Q_m and values of k_r of this order are necessary.

Table III shows the experimental result obtained with $\text{Pb}(\text{Zr}_{0.52}\text{Ti}_{0.48})\text{O}_3$, 0.10 weight percent IrO_2 , and less than 0.50 weight percent MnO in varying amounts.

16'	$\text{Pb}(\text{Zr}_{0.52}\text{Ti}_{0.48})\text{O}_3$ plus 0.50 wt. percent MnO^1 plus 0.15 wt. percent Cr_2O_3	Room temp...	45	970

¹ Denotes equivalent amount of MnO_2 was incorporated in lieu of MnO .

A comparison between samples No. 1 and No. 10 evinces the incorporation of only 0.10 weight percent IrO_2 is already effective for an improvement in k_r . Further, a comparison between samples No. 11 through No. 16 and No. 1 or No. 2 demonstrates that both k_r and Q_m are markedly improved by the coexistence of MnO and IrO_2 . It can further be noted that by comparing samples No. 11 and No. 12 poling at 100°C . is considerably advantageous over poling at room temperature for improvement of k_r , but the value of Q_m is substantially unaffected by the difference in the poling temperature.

Table IV shows similar results with Cr_2O_3 in lieu of IrO_2 .

Table V shows the experimental results with ceramic

75

products consisting of lead titanate zirconate expressed as $\text{Pb}(\text{Zr}_{0.52}\text{Ti}_{0.48})\text{O}_3$ 0.20 wt. percent IrO_2 , and varying amounts of MnO .

A comparison between samples No. 1 and No. 17 shows that the incorporation of 0.20 weight percent IrO_2 alone is effective for an improvement in k_r . Further, a comparison between samples No. 18 through No. 21 and sample No. 1 or No. 17 shows both k_r and Q_m can be markedly improved by incorporation of MnO and IrO_2 as co-existent additives.

TABLE V

No.	Compositional formula	Poling temperature	k_r	Q_m
17	$\text{Pb}(\text{Zr}_{0.52}\text{Ti}_{0.48})\text{O}_3$ plus 0.20 wt. percent IrO_2	Room temp... 100°C -----	59	35 58
18	$\text{Pb}(\text{Zr}_{0.52}\text{Ti}_{0.48})\text{O}_3$ plus 0.01 wt. percent MnO plus 0.20 wt. percent IrO_2	Room temp... 100°C -----	61	45 57
19	$\text{Pb}(\text{Zr}_{0.52}\text{Ti}_{0.48})\text{O}_3$ plus 0.05 wt. percent MnO plus 0.20 wt. percent IrO_2	Room temp...	60	73
20	$\text{Pb}(\text{Zr}_{0.52}\text{Ti}_{0.48})\text{O}_3$ plus 0.20 wt. percent MnO plus 0.20 wt. percent IrO_2	Room temp...	62	56
21	$\text{Pb}(\text{Zr}_{0.52}\text{Ti}_{0.48})\text{O}_3$ plus 0.30 wt. percent MnO plus 0.20 wt. percent IrO_2	Room temp...	60	43

¹ MnO_2 was incorporated in amounts equivalent to 0.20 wt. percent MnO .

² Ir_2O_3 was incorporated in amounts equivalent to 0.20 wt. percent IrO_2 .

Table VI shows the experimental results with ceramic products consisting of lead titanate zirconate expressed as $\text{Pb}(\text{Zr}_{0.52}\text{Ti}_{0.48})\text{O}_3$, 0.20 weight percent MnO and Cr_2O_3 in varying amounts.

A remarkable increase in the value of both k_r and Q_m for samples Nos. 18' and 19' subjected to poling at 100°C . over the sample of 17' subjected to poling at 100°C is readily evident from this embodiment. Further, it is noted that although any one of the values of k_r for samples Nos. 20' through 22' subjected to poling at room temperature is less than the value of k_r for the sample No. 17' containing MnO alone, any one of the corresponding values of Q_m for the former shows a marked increase over the value of Q_m for the latter.

22'	$\text{Pb}(\text{Zr}_{0.52}\text{Ti}_{0.48})\text{O}_3$ plus 0.20 wt. percent MnO plus 0.30 wt. percent Cr_2O_3	Room temp...	45	1,0

¹ MnO_2 was incorporated in amounts equivalent to MnO .

Table VII shows the experimental results with piezoelectric ceramics consisting of lead titanate zirconate $\text{Pb}(\text{Zr}_{0.52}\text{Ti}_{0.48})\text{O}_3$ as the principal constituent components, 0.15 weight percent MnO , and 0.00, 0.05, and 0. weight percent Cr_2O_3 as the coexistent additives.

TABLE VII

No.	Compositional formula	Poling temperature	k_r	Q_m
23'	$\text{Pb}(\text{Zr}_{0.52}\text{Ti}_{0.48})\text{O}_3$ plus 0.15 wt. percent MnO	Room temp... 100°C -----	69	3
24'	$\text{Pb}(\text{Zr}_{0.52}\text{Ti}_{0.48})\text{O}_3$ plus 0.15 wt. percent MnO plus 0.05 wt. percent Cr_2O_3	Room temp... 100°C -----	42	1,0
25'	$\text{Pb}(\text{Zr}_{0.52}\text{Ti}_{0.48})\text{O}_3$ plus 0.15 wt. percent MnO plus 0.10 wt. percent Cr_2O_3	Room temp... 100°C -----	48	1,1

The value of k_r for any one of samples No. 24 and No. 25 subjected to poling at 100° C. becomes a little less than that for corresponding sample 23' containing MnO alone, whereas the value of Q_m for the former has increased markedly over that for the latter. It may be said therefore that these materials, notably No. 24 and No. 25, are adapted for ceramic filter elements for which particularly large values of k_r are called for transducer elements in mechanical filters.

It can be further noted that the value of k_r for either of samples No. 24' and No. 25' subjected to poling at room temperature has been decreased markedly from that for corresponding sample No. 23', whereas the value of Q_m for the former has been markedly increased. It may be said therefore that these materials, notably No. 24 and No. 25 (subjected to poling at room temperature) are adapted for ceramic filter elements for which values of k_r of this order are required.

The values of k_r and Q_m for a ceramic material consisting of lead titanate zirconate expressed as

0.01 weight percent MnO, and 0.30 weight percent IrO_2 (sample No. 22) and subjected in poling at room temperature were 60% and 460, respectively.

The values of k_r and Q_m for a ceramic material consisting of the same principal constituent compositions as sample 22 and 0.30 weight percent IrO_2 (let this be called sample No. 23) were 52% and 325, respectively.

A comparison between these samples readily reveals that the incorporation of traces of MnO (e.g., 0.01 wt. percent) is effective for an improvement of both k_r and Q_m . The corresponding values of k_r and Q_m for the same ceramic materials subject to poling at 100° C. remained substantially unchanged.

Table VIII shows the experimental results with piezoelectric ceramics consisting of PbO , ZrO_2 , TiO_2 so that the generalized formula is:

(for which $x=0.50$, 0.53, and 0.55) incorporating as coexistent additives 0.10 weight percent MnO and 0.10 weight percent IrO_2 . All of these samples were subjected to poling at room temperature.

TABLE VIII
8

No.	Compositional formula	k_r , percent	Q_m
24	$\text{Pb}(\text{Zr}_{0.45}\text{Ti}_{0.55})\text{O}_3$	8	320
25	$\text{Pb}(\text{Zr}_{0.45}\text{Ti}_{0.55})\text{O}_3$ plus 0.10 wt. percent MnO plus 0.10 wt. percent IrO_2	23	1,650
26	$\text{Pb}(\text{Zr}_{0.55}\text{Ti}_{0.45})\text{O}_3$	27	350
27	$\text{Pb}(\text{Zr}_{0.55}\text{Ti}_{0.45})\text{O}_3$ plus 0.10 wt. percent MnO plus 0.10 wt. percent IrO_2	47	1,230
28	$\text{Pb}(\text{Zr}_{0.55}\text{Ti}_{0.45})\text{O}_3$	41	300
29	$\text{Pb}(\text{Zr}_{0.55}\text{Ti}_{0.45})\text{O}_3$ plus 0.10 wt. percent MnO plus 0.10 wt. percent IrO_2	62	970
30	$\text{Pb}(\text{Zr}_{0.55}\text{Ti}_{0.45})\text{O}_3$	38	320
31	$\text{Pb}(\text{Zr}_{0.55}\text{Ti}_{0.45})\text{O}_3$ plus 0.10 wt. percent MnO plus 0.10 wt. percent IrO_2	51	1,470

¹ MnO₂ incorporated in amounts equivalent to 0.10 weight percent MnO₂.

It can be noted that the values of k_r and Q_m for ceramic materials containing 0.10 weight percent MnO and 0.10 weight percent IrO_2 have been improved markedly over those for plain lead titanate zirconate in spite of the changes in the compositional ratio of Zr to Ti shown.

We claim:

1. A piezoelectric ceramic of the general formula $\text{Pb}(\text{Zr}_x\text{Ti}_y\text{Sn}_z)\text{O}_3$

wherein the subscripts denote mole fractions and have the following values: $x=0.9$, $y=1.6$, $z=0.65$, and $x+y+z=1.00$, said ceramic having incorporated therein a first additive of from .01 to .50 weight percent manganese monoxide and a second additive of 0.1 to .30 weight percent iridium dioxide, said first and second additives being coexistent in the ceramic.

2. The ceramic claimed in claim 1 with 0-25 atom percent lead replaced with one or more bivalent elements selected from the group consisting of calcium, strontium and barium.

3. The ceramic claimed in claim 1, wherein one or more of said manganese monoxide and iridium dioxide are replaced with, respectively, a magnesium compound other than manganese monoxide and an iridium compound other than iridium dioxide having the equivalent ion weight.
